WILLIAM M. GOLDSMITH, OF CINCINNATI, OHIO, ASSIGNOR TO THE GOLDSMITH METAL LATH COMPANY, OF CINCINNATI, OHIO, A CORPORATION OF OHIO

METAL LATH AND PROCESS FOR MAKING SAME

Application filed June 24, 1924. Serial No. 722,159.

An object of my invention is to provide structures in the nature of metal lath, wherein the webbing or cross pieces may be extended indefinitely, and wherein such webbing may have its edges disposed in a plane substantially parallel with the faces of the material from which such webbing has been formed.

Another object of my invention is to provide a structure that will entail a minimum loss or wastage of the material from which such structure is formed.

These and other objects are attained by the means described herein, and disclosed in the accompanying drawings, in which:

Fig. 1 is a plan view of a structure embodying my invention, part being in an extended position, and part being cut preparatory to extension thereof.

Fig. 2 is an end view of the device shown in Fig. 1.

Fig. 3 is a plan view of a modified form of structure embodying my invention.

The invention disclosed in Fig. 1 and Fig. 2 hereof shows five transversely extendible lengths or strips. By reference to five transversely extendible lengths shown in Fig. 1, is meant that there are five lengths of material 23, that have their opposed ends disposed immediately adjacent the bars such as 24, prior to expansion or extension of the lath or cut sheet of metal and which lengths or strands on extension or expansion of the lath constitute a single integral band connecting the bars 24.

By reference to the right hand portion of Fig. 1, it will be observed that longitudinal slits 10, 11 and 12 are formed along the bar or edge 13 of the sheet 14, of sheet metal or the like. Transversely extending slits 15, 16 and 17 extend at an angle or obliquely across the face of the sheet 14. It will be observed that slits 15 and 16 stop short of the longitudinally extending slit 18, paralleling slits 10, 11 and 12. The slit 18 extends in parallelism with longitudinal slits 19 and 20. The transversely extending slit 17 communicates at its opposite ends with the longitudinally extending slits 10 and 19. Shorter slits 21 and 22 extend from slit 19 toward slit 11, and stop short of slit 11.

It will be noted that the various transversely extending slits are parallel, one with the other, and that alternate transversely extending shorter slits terminate upon longitudinal slits disposed at opposite ends or sides of the plate 14. Although there are shown but four shorter slits disposed between adjacent longer slits such as 17, it will be readily evident that a larger or smaller number may be disposed between such longer slits, whereby to increase or decrease the number of lengths or strands indicated as 23, that may be developed between and extended between the ends or bars 24 extending longitudinally of the sheet 14. The bars 24 are substantially flat elongated portions of flat sheet metal and may be corrugated or bulged outwardly so as to re-inforce the structure. Attention is called to the fact that the left hand end of the length or strip indicated as 25 in Fig. 1, and the right hand end of the strip or length indicated as 26 in Fig. 1, are disposed in such relationship that when the several lengths are extended to provide a continuous band as shown in the right hand portion of Fig. 1, the bars 24 must be moved longitudinally of one another, so as to dispose the opposite ends of the same bands on the same perpendicular extending between the bars to which said ends are attached. This longitudinal movement of the bars is utilized for turning the lengths 23 so as to dispose the edges 27 of said lengths in planes practically parallel with the faces 28 of the bars 24. By reference to Fig. 2, it will be readily evident that the turning of the lengths 23 as a result of moving the bars 24 apart and longitudinally relative one to the other, serves to place the said lengths on edge, for the reception of plastic and the like, and increases the rigidity of the structure.

It will be readily evident that by using sheets 14 of metal of a heavy gauge and by increasing the number of transverse lengths such as 23, there may be provided a binder that may be utilized to advantage for constructing concrete roads and the like, while lighter gauge material of possibly lesser number of transverse lengths such as 23 would be used to greater advantage as metal lath for walls of houses and the like.

By reference to Fig. 1 it will be noted that by reversing or opposing the direction of the slits in adjacent portions or sections of the sheet, there is very little waste entailed in producing lath embodying my invention.

5 The only waste would be that substantially triangular portions E at the top and bottom of each section and which triangular portions are shown in dotted lines. When considering the extent to which the lath may be extended, this wastage becomes insignificant or negligible.

In Fig. 3 is shown a modified form of lath and embodying the invention. The use of three lengths 33, similar to lengths 23 of which five are shown in Fig. 2, illustrates the flexibility of the invention and that the number of such connected lengths may vary, as well as that the lengths need not be straight, but may be of V shape or of other form. When using V shape strands 33, the metal on opposite sides of the apex 34 of the arms 35 and 36 of the strands turn along the median line of all such strands and develop projections 41 between the arms, and which projections are similar to the projections 42 developed between adjoining strands 33.

What I claim is:

30 1. A metal lath comprising spaced parallel sheet metal bars and integral flat strands connecting adjacent bars, said strands extending substantially perpendicular to and between the adjacent bars, the strands having 35 their flat faces disposed substantially transversely of the bars, and having their edges disposed in substantial parallelism with the faces of the bars.

with the faces of the bars.

2. A metal lath comprising spaced parallel sheet metal bars and integral flat bands connecting adjacent bars, each band comprising a plurality of strands, said bands extending substantially perpendicular to and between the adjacent bars, the bands having their flat faces disposed substantially transversely of the bars, and having their edges disposed in substantial parallelism with the faces of the bars.

3. The process of making expanded metal lath comprising slitting each of adjacent areas of a sheet of metal on a plurality of connected bias lines for providing strand portions, then expanding the slitted portions thereof and bringing the ends of the strand portions into substantial perpendicularity with the sheet metal intermediate such ends.

4. The process of slitting sheet metal along a series of connecting lines extending in substantial parallelism with one another and 80 inclined to the length and width of sheet metal and then extending the slit sheet metal in the direction of the width of the sheet.

5. The process of making expanded metal
65 lath comprising slitting each of adjacent par-

allel areas of a sheet of metal along a series of connected substantially parallel lines whereby to form a plurality of parallel bars spaced by slotted areas, the parallel lines being oblique to and between the bars, and then extending the slotted portions of the sheet and moving the bars relative to one another for expanding the sheet and for turning the slotted portions of the sheet at substantially 90 degrees to their original positions. 70 75

6. The process of making expanded metal lath comprising slitting the central portion of a sheet of metal along a series of connected substantially parallel lines whereby to provide substantial lateral bar sections disposed on opposite sides of the slit portion of the sheet, the said parallel lines extending on the bias relative the bars, and then moving the bars apart and longitudinally of one another to positions such that the bars extend in substantial parallelism and the bias cut material between the bars extends substantially perpendicular to and between the bars. 80 85 90

7. A metal lath comprising spaced parallel sheet metal bars, each of the bars having a face disposed on each side of the lath, the faces on common sides of the bars lying in the same general plane, and integral flat strands connecting adjacent bars, the strands being turned edgewise relative to the bars and extending perpendicular to and between adjacent bars. 95

8. A lath of expanded sheet metal comprising spaced parallel bars, each of the bars having a face disposed on each side of the lath, the faces on common sides of the bars being aligned, and integral strands connecting adjacent bars and having bias cut connections with the bars and extending substantially perpendicular to and between the bars, the strands being edgewise relative the bars. 100 105

9. The process of making expanded metal 110
lath comprising slitting each of two spaced
parallel portions of a sheet of metal where-
by to provide parallel bars at each side of
the slitted portions and between the slitted
portions, the slitted portions being cut along 115
lines at a bias to the parallel bars, and the
bias slits on opposite sides of the intermedi-
ate bar extending in opposite directions, and
then moving bars at the outer sides of the
slitted areas apart for extending the slitted 120
material to positions in substantial parallel-
ism with similar slitted portions and to po-
sitions on edge and substantially perpendic-
ular to all the parallel bars.

In testimony whereof, I have hereunto ¹²³ subscribed my name this 16th day of June, 1924.

WILLIAM M. GOLDSMITH.
